UNITED STATES PATENT OFFICE.

JOHN W. HUDSON, OF WELLINGTON, ILLINOIS.

WOOD-SHAPING MACHINE.

SPECIFICATION forming part of Letters Patent No. 268,405, dated December 5, 1882.

Application filed June 15, 1882. (No model.)

To all whom it may concern:

Be it known that I, JOHN W. HUDSON, a citizen of the United States of America, residing at Wellington, in the county of Iroquois and State of Illinois, have invented an Improvement in Shaping-Machines, of which the following is a specification.

My invention relates to a machine for cutting and finishing hames or other irregular shapes.

The object of my invention is to provide a machine for working irregular forms, particularly adapted for making hames for harness; and my invention consists, first, in a peculiar arrangement of movable revolving spindles carrying the cutting or finishing heads, and moved to conform to the shape of the work by camways in a reciprocating table on which the work is placed; second, in a double set of movable spindles, one set of which is provided with cutting and the other with smoothing or finishing heads, and so arranged that while one set is in position for work the other is thrown out; and, third, in certain combinations and arrangement of parts, as hereinafter fully described with reference to the accompanying drawings, in which—

Figure 1 is a plan view of my improved machine. Fig. 2 is a side elevation, Fig. 3 a longitudinal sectional elevation, and Fig. 4 a transverse sectional elevation, of the same. Figs. 5 to 10, inclusive, are views of some of the various parts shown in detail, and more directly referred to hereinafter.

Like parts are represented by similar letters of reference throughout the several views.

In the said drawings, A A represent the main frame of the machine, which I prefer to make of iron, consisting of the side pieces A' A', each cast in a single piece, and firmly connected together and braced above and below to secure the proper strength and stability.

B is the reciprocating or sliding table, which consists substantially of an upper and lower table, B' and B'', which are made exactly alike, and firmly connected together and securely braced by connecting-pieces b and braces b'. The table B' is provided on each side at the top and bottom with V-shaped ways e, which slide in correspondingly-grooved pieces e, secured to the main frame A A at the bottom,

and similarly-formed projections e' at the top.

Running lengthwise of the table B in the top and bottom plates, B' and B'', are camways C C, bounded on each side by steel plates P, 55 through which project the spindles S S and S' S', which are journaled above and below in sliding bearings d d', which move freely in slides a a', extending across the machine above and below the table B, those, a', at the bottom 60 having their ends rigidly attached to the side frame-pieces A' A', while those, a, at the top are arranged to be raised or lowered vertically, as and for the purpose hereinafter more fully set forth. The spindles S and S' are turned down 65 at the upper end, where they enter the bearings, with a shoulder at the bottom of the bearings, and are provided at the top with nuts n n', which prevent any end-play of the spindles through the bearings d, but at the 70 lower end are left full size, and are free to move vertically through the bearings d'.

To the spindles S, directly under the bearings d, are secured the cutter-heads h, which may be of any desired size, provided with 75 properly-shaped cutters to correspond to the work to be done, and having their lower ends resting directly on the steel plates P at the sides of the camways C. In a similar manner to the spindles S' are secured the finishing or 80 smoothing heads h', which are made similar in shape to the cutting-heads h, but instead of cutters are provided with pieces, h'', of steel, cut in the manner of a rasp. (See Fig. 10.) The upper slides, a a, on which the bearings d 85 move, are arranged in pairs secured together at each end, and arranged to move vertically in vertical recesses a' a'' in side pieces D, secured on each side of the main frame A A. Each set of slides are connected together at 90 the ends by cross-bars e', to the center of each of which is attached a link, e'', connected at its other end to an oscillating lever, L, secured on a square rod or shaft, f, journaled at each end in bearings f' on the side pieces D, and 95 provided at one end with a hand-lever, E, which extends at its outer end through the adjustable pressure-yoke K, secured to the side of the frame A A. (See Figs. 2 and 7.) By this arrangement, upon raising the hand-lever E the cutting-heads h are brought in position for work, while the finishing-heads h' are raised up out 100

of the way, as shown in Fig. 3, and vice versa. The adjustable yoke K, referred to above, is shown in detail in Fig. 8, and consists of a pipe or sleeve, g, secured to the main frame A A, bored out for a portion of its length from each end, with the ends i i of a loop, l, fitting therein and resting against springs n' n'. Secured to the inner side of the loop l is a bar, l', having at each end a series of notches, o o, with one of which a projection, o', on the lever E is made to engage by means of a spring, s, secured at one end to said lever and bearing against the opposite side of the loop l.

R R are what I term the "pressure-rollers," one of which is placed opposite each cutting and finishing head, and consists of a roller, r, provided with a spindle, r', journaled in a sliding box, d², sliding between the bars a a, and connected to the bearing d of the spindle S by a spring, s', secured to the bearing by a set-screw, s², passing through a slotted hole, s³, which renders it adjustable. (See Fig. 9 for detail.) The spindle r' of the roller is turned down for a portion of its length and a coiled spring, t, placed thereon, thus allowing the roller to yield either vertically or laterally. The hame or other article to be shaped is placed on the top of the table at F between the camways C, which are shaped at this point to correspond with the shape it is desired to cut. The cutting-spindles S S are revolved by means of belts G, running from a suitable source of power to pulleys p², secured thereon, which are in turn connected to pulley p³ on the finishing-spindles S' by belts G'. The pulleys p³ are not secured to the spindles S', but run loose thereon, being supported in their places by a stand, H, which rests on the bearing d' and encircles the spindle above and below the lower plate, B², of the table, with the connecting-shank j extending through the camway C. (See Fig. 5.) Secured to the spindles S' are clutch-collars u u, which, when the finishing-heads h are lowered into position for work, engage with similar clutches on the top of the pulleys p³, and thus revolve the spindles S' S'. When the heads h' are raised out of position the clutches U become disengaged from the pulleys p³, which then run loosely on the spindles S' while said spindles remain at rest.

In making hames with this machine the hame is first steamed and bent in the rough to something near the required shape. The sliding table B is pulled back to its full extent, and the hame placed thereon at F, which is provided with small points or stickers to hold it in place. The cutting-spindles are lowered to their position and started to revolving. The table is then passed through. The spindles S S, moved by the camways C C, move back and forth on the slides a a to correspond to the shape of the hame, the pressure-rollers R serving to hold it in place. There being two cutting-heads—one on each side—the hame is cut out on both sides at once. After the hame has passed the cutting-heads the hand-lever E is

pushed down, which raises the cutting and at the same time lowers the finishing heads into position, as before described. The table is now drawn back and the hame thoroughly smoothed by the revolving rasps. It is sometimes desirable to have the hame a little thicker in the middle than at the ends. This is accomplished by having the steel plates P, on which the heads h or h' rest when at work, slightly tapered, which gives the spindles a slight vertical movement, which is permitted by reason of the adjustable pressure-yoke K. The steel plates P are secured to the tables B' B² by screws e⁵ e⁶, which extend through slotted holes e⁴ e⁴ in the table, (see Fig. 9,) and are thus rendered adjustable in case of wear.

The camways C at the rear end of the table extend clear out, and a plate, P, being secured on the said ends of the table at the top and bottom, as shown in Fig. 6. By removing these plates the table B may be withdrawn from the frame N N and reversed, bringing the part B² to the top. This will reverse the camways, and furnish the means of making right and left hames with the same machine.

If desired, the table B may be fed automatically by the addition of a rack and pinion, or other well-known device for this purpose. The hand-lever E may be also arranged to automatically change the position of the cutting and finishing heads; or it may be done by hand.

It will be evident from the above description that by changing the shape of the camways in the table and the shape of the cutters irregular forms of an infinite variety may be cut with this machine of varying sizes, shapes, and thicknesses.

Having thus described my invention, what I claim as new, and desire to secure by Letters Patent, is—

1. A double set of movable revolving spindles moved to conform to the shape desired by camways in a reciprocating table, one set provided with cutting-heads and the other with smoothing or finishing heads, in combination with a lever, whereby one set is thrown out of and the other into position for work, substantially as described and shown.

2. In combination with the movable revolving spindles S S', a reciprocating table, B, composed of the upper and lower plates, B' B², provided with camways C, and so constructed that it may be reversed for cutting right and left forms, substantially as shown and described.

3. The combination of the frame A, bars a a', sliding bearings d d', spindles S S', journaled in said bearings, hand-lever E, oscillating levers L L, connected by rod f, and the cross-bars e', and links e², connecting the sliding bearings and oscillating levers, substantially as and for the purpose described.

4. The combination of the frame A, having grooved pieces c c and projections c' c', the reciprocating table B, composed of the top and

bottom plates, $B' B^2$, having suitable connections or braces, $b b'$, and V-shaped ways $e e$, the camways $C C$, located on the plates $B B'$, and bounded by adjustable steel plates $p p$, the spindles $S S'$, journaled in bearings adapted to slide on bars extending across the machine above and below the table B , the upper bearings having a vertical adjustment, and said spindles being provided with suitable 5 shaping and finishing cutters, the adjustable

pressure-yoke K , spring pressure-rollers $R R$, and suitable actuating mechanism, substantially as shown and described.

In testimony whereof I affix my signature in presence of two witnesses.

JOHN WESLEY HUDSON.
